CLAIM

The ornamental design for a removable walker grip cushion, as shown and described.

DESCRIPTION

FIG. 1 is a front elevational view of the removable walker grip cushion showing our new design;

FIG. 2 is a rear elevational view thereof;

FIG. 3 is an enlarged left side elevational view thereof;

FIG. 4 is an enlarged right side elevational view thereof;

FIG. 5 is a top plan view thereof;

FIG. 6 is a bottom plan view thereof;

FIG. 7 is an enlarged cross-sectional view thereof taken along line 7—7 of FIG. 2; and,

FIG. 8 is a perspective view thereof showing the invention attached to a walker handle.

The broken line showing of a walker handle in FIG. 8 is for illustrative purposes only and forms no part of the claimed design.
